GAME BOARD

Edward J. Wright, Cresskill, N. J.

Application March 26, 1957, Serial No. 45,435

Term of patent 14 years

(Cl. D34—5)

The figure is a plan view of a game board, showing my new design.

The board is of conventional thickness.

This is a continuation-in-part of my earlier application, Serial No. D. 38,883, filed November 14, 1955, now abandoned.

I claim:

The ornamental design for a game board, as shown and described.
